UNITED STATES PATENT OFFICE.

NELLA ROMANO SANSETTA, OF BROOKLYN, OHIO.

BRASSIÈRE.

Application filed March 20, 1923. Serial No. 626,283.

To all whom it may concern:

Be it known that I, NELLA ROMANO SANSETTA, a citizen of the United States, residing at Brooklyn, in the county of Cuyahoga and State of Ohio, have invented certain new and useful Improvements in Brassières, of which the following is a specification.

My invention relates to improvements in brassières, the invention relating more particularly to the front or bust supporting sections thereof.

The primary object of the invention is to provide a generally improved brassière of the class or type indicated which will be exceedingly simple in construction, cheap of manufacture and efficient in use.

A further and very important object is the provision of improved elastic bust supporting sections each made up of elastic webbing members of uniform width throughout and diverging from each other toward the median front forming diverging openings, together with suitable pockets of pervious or Shirred material connected to said elastic web members and covering said intervening spaces or diverging openings, the construction and arrangement of such parts facilitating the formation of the elastic bust sections of any desired form or contour.

A further and very important object is the formation of elastic bust supporting sections through the medium of inwardly diverging elastic webbing strips of uniform width throughout so that such elastic strips may be cut from elastic webbing of commercial or staple stock, said strips being arranged to provide the desired contour with suitable openings therebetween to be covered by suitable bust receiving pockets preferably formed of pervious Shirred material.

There are other features of the invention residing in elemental combinations and particular construction of parts, all as will hereinafter more fully appear.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part of this specification, Figure 1 is a

perspective view of a brassière constructed in accordance with this invention.

Fig. 2, a fragmentary perspective view of the inner or connecting edge portion of one of the bust sections, and illustrating in particular the pair of spaced elastic webbing strips and pocket forming material secured to the latter and adapted to cover the spaces therebetween.

Similar numerals of reference designate like parts throughout all the figures of the drawings.

The improved brassière preferably comprises non-elastic pervious back and side sections 1 and 2, respectively, the side sections 2 being preferably connected at their front by the improved bust supporting sections to be now described.

The bust supporting sections are preferably divided vertically along the median front, and in which instance, each bust section is made up of spaced inwardly diverging elastic webbing strips 3, of uniform width throughout forming diverging openings or spaces 3^a, therebetween. The elastic webs 3 are provided on their front or exterior portions with bust receiving pockets 3^b, formed of some suitable and convenient pervious light weight material and preferably Shirred as shown. The pocket material 3^b is preferably cut to form laterally curved or web shaped sections providing curved or convex shaped upper and lower edges 3^c, receiving a line of stitches which it will be observed are thus substantially spaced from the edges 3^a of the spaces between the web strips 3.

The inner or adjacent edges of the bust sections formed by the web strips 3 and the pockets 3^b are provided with reinforced binding strips 3^d, provided with suitable flexible reinforcing members 3^e (see Fig. 2) and provided with a series of hooks 3^f, and eyes 3^g, and by which the bust sections may be detachably connected together. The outer ends of the elastic webs 3 may be connected to each other and to the front edges of the side sections 2 by means of vertically extending binding strips 3^h, which, in the present instance, are without reinforcement. The back and side sections 1 and 2 are provided with suitable reinforced strips 3ⁱ, having reinforcing members 3^j, said strips 3ⁱ, in the present instance, being extended forming shoulder straps 3^k, extending for

wardly and connected to the upper bust section forming webs 3. In the present instance the forward portions of the straps 3^k are provided with extension loops 3^m, secured by a line of stitching 3ⁿ, and which may, if desired, be let out for lengthening the shoulder straps.

As a means of adjusting and holding the bust sections in proper relative position 10 with respect to the corset, a pendant strap 4, may be provided at its lower end with an attaching element such as a hook 5, adjustably mounted thereon and adapted to be attached to the corset below in a well 15 known and understood manner.

Having thus described one of the embodiments of my invention, without having attempted to set forth all the forms in which it may be made, or all the modes of its use, 20 what I claim and desire to secure by Letters Patent is,—

1. A brassière, comprising non-elastic pervious back and side sections, bust supporting sections made up of spaced inwardly diverging elastic webbing strips of uniform width, and Shirred pervious material

secured to said webbing strips and extending over said spaces forming pervious bust receiving pockets.

2. In a brassière, a bust supporting section made up of vertically spaced horizontally extending elastic web strips forming intervening bust receiving spaces, pervious shirred material on said elastic web strips extending over said spaces forming pockets, and vertically extending binding strips extending over the edges of said elastic web strips and pocket forming material.

3. A brassière, comprising back and side sections, elastic webbing strips forming bust supporting sections and diverging toward the median front forming diverging openings, shirred pockets on said webbing strips covering said diverging openings, vertical binding strips at the side and central portions of said elastic strips, shoulder straps for supporting said bust and back sections, and a pendant strap for securing said bust sections to a corset.

In testimony whereof I have affixed my signature.

NELLA ROMANO SANCETTA.
